UNITED STATES PATENT OFFICE

DAVID S. JACOBUS, OF MONTCLAIR, NEW JERSEY, ASSIGNOR, BY MESNE ASSIGNMENTS,
TO FULLER LEHIGH COMPANY, A CORPORATION OF DELAWARE

SUPPORT FOR WATER-COOLED WALLS OF BOILERS

Application filed November 20, 1926. Serial No. 149,561.

This invention relates to a support for furnace walls that may be cooled by water circulating through tubes, which in turn may be connected to the water circulation system 5 of the boiler.

The invention will be understood from the description in connection with the accompanying drawings, in which Fig. 1 is a section partly broken away, showing an embodiment of the invention; Fig. 2 is a section along the line 2—2 of Fig. 1; Fig. 3 is a plan view of one of the supports; Fig. 4 is a section along the line 4—4 of Fig. 3; and Fig. 5 is an end view of the support 15 shown in Fig. 3.

In the drawings reference character 1 indicates a furnace of a boiler in the lower portion of which a stoker (not shown) may be located. A water tube boiler may be 20 located above the furnace 1 having inclined tubes 2 connected to headers 3 and 4. The other parts of the boiler are not shown in detail. The usual mud drum 5 is shown located below the headers 4.

25 The rear wall of the furnace is indicated at 6 and is cooled by means of water tubes 7 that extend vertically along the inner side of the rear wall of the furnace, the upper ends being bent outwardly and extending 30 through the wall 6 into a header 8 that is preferably inclined to prevent pocketing of steam therein, each successive tube 7 being made slightly longer than the preceding one to accommodate this arrangement of the 35 header 8. The lower ends of the tubes 7 are bent outwardly and terminate in a header 9 that is suspended by means of straps 10 from a support 11 so that the header can move slightly due to expansion and contraction of the tubes 7. The headers 8 and 9 can be connected to the water circulation system of the boiler in any convenient manner, as, for example, by pipes connected to the headers 8 and 9.

40 Supports 15 made in the shape of hollow boxes that are rectangular in cross section and arranged side by side are located below the rear wall 6 and support the same, these hollow supports 15 being in turn supported 45 by means of I-beams 16 extending parallel

with the wall 6. The supports or hollow boxes 15 have their outer ends 17 preferably flush with the outer surface of the wall 6 and these outer ends are open to the atmosphere. The other ends of these boxes are beveled 55 and have rearwardly inclined plates 18 extending across the same. These plates are provided with holes 19 for admitting air into the furnace. The boxes 15 have elongated openings 20 in their upper walls through 60 which tubes 7 extend and are made sufficiently large to enable the tubes to move as they change in length due to expansion and contraction.

It will be obvious that the hollow box supports 15 not only support the wall 6 of the furnace, but that they also permit ingress of air into the furnace for combustion purposes and at the same time this air aids in cooling the lower portion of the wall. 65

I claim:

1. In a furnace, a wall having a row of vertically extending tubes disposed along the inner side thereof and having their lower ends bent outwardly and connected to a 75 header disposed outside the wall, and a plurality of boxes disposed beneath said wall and constructed to conduct air to the furnace, each of said outwardly bent tube ends passing through one of said boxes and said 80 boxes supporting the wall above them.

2. In a furnace, a wall having a row of vertically extending tubes disposed along the inner side thereof and having their lower ends bent outwardly and connected to a 85 header disposed outside the wall, and a plurality of boxes disposed beneath said wall and constructed to conduct air to the furnace, said outwardly bent tube ends passing through said boxes, said boxes having the 90 upper edges of their inner ends substantially flush with the inner side of the wall.

3. In a furnace, a wall having a row of vertically extending tubes disposed along the inner side thereof and having their lower ends bent outwardly and connected to a header disposed outside the wall, a plurality of boxes disposed beneath said wall and constructed to conduct air to the furnace, said 95 outwardly bent tube ends passing through 100

said boxes, said boxes having the upper edges of their inner ends substantially flush with the inner side of the wall, and said inner ends being inclined downwardly and outwardly from said upper edges.

5. 4. In a furnace, a support having a box disposed thereon, said box having one end disposed within the furnace and inclined downwardly and outwardly, a wall disposed above said box, means for admitting air through the box into the furnace, the outer end of said box being open, a header disposed outside the wall adjacent said open end, and a tube disposed on the inner side 15 of the wall and having its lower end bent outwardly and connected to said header, said outwardly bent end extending through a hole in said box and through the outer end thereof.

20. 5. In a furnace, a vertically extending wall, a box disposed beneath said wall and forming a support therefor, a vertically extending tube in said wall having its lower end bent outwardly and extending through 25 said box and through openings in the top and outside thereof, a header disposed outside the wall and connected to the tube, and means for passing air through said box into the furnace, said openings being large 30 enough to permit lateral movement of the tubes therein.

6. In a furnace, a wall having a tube adjacent the inner face thereof, a header disposed outside the wall, an end of the tube 35 being bent outwardly and connected to said header, a box having openings in one side and the outer end thereof through which said end of the tube passes, and means for passing air through said box into the furnace, said openings being large enough to 40 permit lateral movement of the tubes therein.

DAVID S. JACOBUS.
